UNITED STATES PATENT OFFICE.

BENNO WIELER, OF LAIRD, SASKATCHEWAN, CANADA.

THRESHING-MACHINE.

1,254,750.

Specification of Letters Patent. Patented Jan. 29, 1918.

Application filed September 28, 1916. Serial No. 122,675.

To all whom it may concern:

Be it known that I, BENNO WIELER, a subject of the King of England, residing at Laird, in the Province of Saskatchewan and Dominion of Canada, have invented certain new and useful Improvements in Threshing-Machines, of which the following is a specification, reference being had to the accompanying drawings.

10 This invention relates to certain improvements in threshing machines and it is an object of the invention to provide a machine of this general character having novel and improved means whereby the bundles or 15 sheaves will be readily and conveniently conveyed to the threshing cylinder and whereby said operation may be had during the travel of the machine.

The invention also has for an object to 20 provide a novel and improved machine of this general character of a portable type and wherein a conveying mechanism is employed for carrying the bundles or sheaves to the threshing cylinder and wherein means is 25 provided for lifting into proper engagement with the conveyer mechanism a sheaf or bundle which may be lying upon the ground.

The invention also has for an object to 30 provide a novel and improved machine of this character wherein the same is power operated and whereby the engine may be employed to drive the machine over the surface and also to operate the various movable parts employed in the threshing or other 35 operations.

It is also an object of the invention to provide a machine of this general character with a novel and improved grain separating means which includes a revolving drum or 40 cylinder into which the threshing cylinder discharges together with means positioned within said revolving drum on cylinder for separating the grain.

The invention has for a still further object to provide a novel and improved grain separating means wherein a conveyer is positioned within a revolving cylinder or drum and upon which the grain separated by the drum is discharged and wherein said conveyer discharges upon a screening element 50 also disposed within the revolving cylinder or drum.

The invention consists in the details of construction and in the combination and arrangement of the several parts of my improved threshing machine whereby certain

important advantages are attained and the device is rendered simpler, less expensive and otherwise more convenient and advantageous for use, all as will be hereinafter 60 more fully set forth.

The novel features of the invention will hereinafter be definitely claimed.

In order that my invention may be the 65 better understood, I will now proceed to describe the same with reference to the accompanying drawings, wherein

Figure 1 is a view in side elevation of a threshing machine constructed in accordance with an embodiment of my invention; 70

Fig. 2 is a longitudinal vertical sectional view taken through the machine as herein embodied, certain of the endless aprons or conveyers being shown in elevation;

Fig. 3 is a view partly in top plan and 75 partly in horizontal section of the machine as herein set forth;

Fig. 4 is an enlarged transverse sectional view taken through the grain separating means and the adjacent portion of the machine; and

Fig. 5 is a fragmentary view in perspective of the lifting member as herein disclosed.

As disclosed in the accompanying drawings, F denotes a frame of predetermined dimensions and configuration and which is supported by the wheels W. The rear wheels W are adapted to rotate with their axle or shaft 1. 85

The axle or shaft 1 is provided with a gear 2 in mesh with the gear 3 loosely mounted upon the transmission shaft T driven by the engine E. The engine E may be of any preferred type but preferably internal combustion. 90

Coacting with the gear 3 is a clutch member 4 keyed to the shaft T but capable of movement longitudinally thereof whereby the gear 3 may be caused to rotate with the shaft T as desired, or vice versa. As the clutch member 4 may be moved in any manner which best meets the requirements of practice, it is thought that a detail description and illustration of such operating means 105 is unnecessary.

Mounted upon the frame F is the housing or superstructure H and which has rotatably supported between its side walls the threshing cylinder A of a conventional type and which coacts with the concave B. 110

The axle 5 of the cylinder A extends be-

yond one side of the housing or superstructure H and the extended portion thereof is provided with a pulley 6 around which is disposed a belt 7 which is also directed around a pulley 8 fixed to the shaft 9. The shaft 9 extends transversely of the frame F at a predetermined position below the cylinder A and has affixed thereto the gear wheel 10 in mesh with the gear wheel 11 carried by the vertically disposed shaft 12 operatively supported in any desired manner by the frame F and the housing or superstructure H. The lower end of the shaft 12 is provided with the gear 14 in mesh with the gear 15 loosely mounted on the transmission shaft T and with which coacts a clutch member 16 keyed to said shaft T but capable of movement longitudinally thereof whereby the shaft 12 may be caused to operate when desired. The manner of operating the clutch 16 forms no particular part of my invention and as any well known structure may be employed, it is thought that a detail description and illustration thereof is unnecessary.

In advance of the threshing cylinder A are the vertically spaced feeding rollers 17 and 18 which serve to facilitate the delivery of the straw to the cylinder A.

Discharging between the rollers 17 and 18 is a chute 19 through which the grain and straw falls after the bundles or sheaves have been severed by the cutters 20.

21 and 22 denote coacting endless conveyers disposed on predetermined inclines, the upper conveyer 22 being operatively engaged with the shafts 23 rotatably supported by the side boards 24, while the lower conveyer 21 is operatively engaged with the shafts 25 rotatably supported by the side boards 26. The lower shaft 23 of the upper conveyer 22 and the upper shaft 25 of the lower conveyer 21 are operatively connected, as at 27, whereby it will be perceived that said conveyers 21 and 22 will be caused to move in unison and in the same general direction. The upper shaft 23 of the conveyer 22 extends beyond a side board 24 and said extended portion has affixed thereto a pulley 28 around which is disposed a belt 29 which is also directed around a pulley 30 secured to an extended portion of the shaft 31 of the lower feeding roller 17. Also disposed around the pulley 30 is the crossed belt 32 which is operatively engaged with the pulley 8 hereinbefore referred to. By this arrangement it will be perceived that the lower feeding roller 17 and the conveyers 21 and 22 will be caused to properly operate.

The cutters 20 are mounted upon a shaft 33 which extends beyond a side of the housing or superstructure H and said extended portion is provided with a pulley 34 around which is disposed a belt 35 which is directed under and in contact with a pulley 36 carried by an extended portion of the shaft 37 of the

upper feeding roller 18. The belt 35 is also disposed around the pulley 6 hereinbefore referred to and over and in contact with a pulley 38 fixed to an extended portion of a shaft 39. The shaft 39 extends transversely of the housing or superstructure H for a purpose which will hereinafter be more particularly referred to.

Interposed between the lower ends of the side boards 26 is a bar 40 provided with the forwardly directed tines 41. The tines 41 are adapted to substantially contact with the ground or surface over which the machine travels so as to raise the sheaves or bundles which may be lying upon said ground or surface so as to be properly engaged with the conveyer 21.

42 denotes the drive shaft of the engine E and with which coacts the clutch member 43 keyed to the shaft T but capable of movement longitudinally thereof so that it will be perceived that when desired the shaft T may be caused to rotate or rendered inactive.

C denotes a hollow cylinder or drum disposed longitudinally of the frame F and positioned adjacent the cylinder A. The cylinder or drum C is adapted to rotate, and as herein disclosed, the opposite end portions of said cylinder or drum C extend within cylindrical openings 44 produced in the transversely disposed walls 45 included in the housing or superstructure H, and coacting with said cylinder C and wall 45 are the anti-friction members 46 whereby it will be perceived that said cylinder or drum C may be caused to rotate with a minimum of frictional resistance.

Disposed around the cylinder or drum C is a drive belt 47 which is also disposed around a pulley 48 loosely mounted upon the transmission shaft T and with which coacts the clutch member 49 keyed to said shaft T but capable of movement longitudinally thereof, whereby the rotation of the cylinder or drum C may be readily controlled. The clutch member 49 is adapted to be adjusted relative to the pulley 48 in any desired manner.

The opposite ends of the cylinder or drum C are open and the inner surface or wall thereof is provided entirely therearound with the longitudinally disposed angular grooves or channels 50 which afford pockets or buckets to receive the grain separated from the straw, and as said cylinder or drum C rotates the grain within the grooves or channels 50 will be delivered upon the upper stretch of the endless conveyer 51. As is particularly disclosed in Fig. 4 it is to be noted that the grooves or channels 50 are arranged one immediately adjacent the other so that the grain will be substantially continuously delivered upon the conveyer 51. The conveyer 51 is operatively engaged with the shafts 52 and 53 which are supported

5 by the table 54 which extends entirely through the cylinder or drum C and is supported in applied position through the medium of the cross beams 55 included in the 10 housing or superstructure H. It is also to be noted that the table 54 is positioned above the axial center of the cylinder or drum C.

10 The shaft 53 is positioned rearwardly of the cylinder or drum C while the shaft 52 is positioned in close proximity to an opening 56 formed in the table 54 adjacent the forward end thereof and at a point within the cylinder or drum C. The conveyer 51 travels through said opening 56 and causes the grain collected thereby to be discharged through said opening and upon the vibrating screen 57 extending entirely through the cylinder or drum C and arranged below 20 the table 54, as is believed to be clearly shown in the accompanying drawings.

25 As herein disclosed, the screen 57 is supported by the hangers 58 and the forward end of said screen 57 is operatively engaged through the medium of the pitman 59 with the cranks 60 of the shaft 39 hereinbefore referred to. It will therefore be understood that as the shaft 39 is rotated the requisite vibration will be imparted to the screen 57.

30 The screen 57 is of a width substantially equal to the width of the bore of the cylinder or drum C and as the cylinder or drum rotates, the straw as it is carried upwardly by said cylinder or drum C will engage the screen 57 and be thrown downwardly, whereby a thorough separation of the grain is assured. The screen 57 also permits the passage of chaff and dirt therethrough so that when the grain is discharged from the screen 57 into the receptacle 61, the same will substantially be free 40 of impurities.

45 Coacting with the receptacle 61 is an elevator 62 including the endless carrier 63 which is driven from the shaft 64. The shaft 64 has an extended portion provided with a pulley 65 around which passes the crossed belt 66. The belt 66 also passes around the pulley 67 secured to an extended portion of 50 the shaft 53. The drum 67 has also disposed therearound the belt 68 which coacts with the pulley 6 hereinafter referred to, whereby it will be perceived that the conveyer 51 and carrier 63 will be caused to 55 properly operate.

60 Positioned below the concave B is an apron 69 which serves to deflect any grain dropping between the bars of the concave B within the cylinder or drum C and adjacent the lower portion thereof, as is believed to be clearly shown in Fig. 2 of the accompanying drawings.

65 From the foregoing description, it is

thought to be obvious that a threshing machine constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself 70 to the precise arrangement and formation of the several parts herein shown in carrying out my invention in practice, except as hereinafter claimed.

75 I claim:

80 1. A grain separator including a cylindrical tubular body open at opposite ends and mounted for rotary movement about substantially a horizontal axis, means for rotating the same, a table disposed through the cylindrical body and supported independently thereof, said table within the cylindrical body being provided with an opening adjacent the receiving end of said cylindrical body, an endless conveyer supported by the table and extending through the opening of the table, the upper stretch of said conveyer traveling in a direction toward the opening in the table, a screen disposed through the cylindrical body below the table, and means for delivering grain within the cylindrical tubular body at the receiving end thereof and below the screen.

85 2. A grain separator including a cylindrical tubular body open at opposite ends and mounted for rotary movement about substantially a horizontal axis, means for rotating the same, a table disposed through the cylindrical body and supported independently thereof, said table within the cylindrical body being provided with an opening adjacent the receiving end of said cylindrical body, an endless conveyer supported by the table and extending through the opening of the table, the upper stretch of said conveyer traveling in a direction toward the opening in the table, a screen disposed through the cylindrical body below the table, said screen being supported independently of the cylindrical body, means for vibrating said screen, and means for 90 delivering grain within the cylindrical tubular body at the receiving end thereof and below the screen.

95 100 In testimony whereof I hereunto affix my signature in the presence of two witnesses.

105 BENNO WIELER.

110 Witnesses:

115 W. E. LAWSON,
C. M. FORREST.
